UNITED STATES PATENT OFFICE.

HUGH BURT MITCHELL, OF CANTON, OHIO, ASSIGNOR TO ANDREW M. McCARTY, ALBERT HOEFFER, AND ADAM C. McDOWELL, OF SAME PLACE.

DENTAL HANDPIECE.

SPECIFICATION forming part of Letters Patent No. 663,086, dated December 4, 1900.

Application filed April 2, 1900. Serial No. 11,092. (No model.)

To all whom it may concern:

Be it known that I, HUGH BURT MITCHELL, a citizen of the United States, residing at Canton, in the county of Stark and State of Ohio, have invented certain new and useful Improvements in Stop Attachments for Dental Handpieces; and I do hereby declare that the following is a full, clear, and exact description of the same, reference being had to the annexed drawings, making a part of this specification, and to the figures of reference marked thereon, in which—

Figure 1 is a side elevation showing the different parts properly assembled. Fig. 2 is a top view showing the different parts properly connected. Figs. 3 and 4 are detached views of the connecting-screws. Fig. 5 is a detached view of the shield. Fig. 6 is a view showing the clutch-shifting bar or plate with its operating-handle. Fig. 7 is a detached perspective view of the clutch-shifting bar or plate. Fig. 8 is a view showing the shaft designed to be connected to the cable and to the shifting clutch, also showing screw-threaded disks for connecting the cable-sleeve and the clutch-retaining cylinder. Fig. 9 is a detached view of the shifting clutch. Fig. 10 is a detached view of the sliding-clutch-containing cylinder. Fig. 11 is a view showing the rear end or portion of the handpiece. Fig. 12 is a vertical section through Fig. 8, except that the shaft is shown full. Fig. 13 is a vertical section of the sliding-clutch cylinder and clutch. Fig. 14 is a view showing the rear end of the handpiece and its retaining-shaft.

The present invention has relation to a stop attachment for dental handpieces; and it consists in the different parts and combination of parts hereinafter described, and particularly pointed out in the claims.

The object of the present invention is to provide a means to instantaneously stop and start the rotation of the various kinds of tools designed to be connected to a dental handpiece without stopping the rotation of the cable and the sliding or interlacing clutch.

Similar numerals of reference indicate corresponding parts in all the figures of the drawings.

50 In the accompanying drawings, 1 represents

the handpiece proper, which may be of the form shown, and preferably is of such form, and is constructed in the ordinary and usual manner and forms no particular part of the present invention, except that such handpiece 55 must necessarily be employed to carry out the full purpose of the invention.

It will be understood that the handpiece or portion 1 is to be provided with the ordinary parts to connect the various tools designed 60 to be used or employed in various kinds of dental work in which a rotary motion is to be imparted to the tool used.

The handpiece 1 is provided with the rotating bar or shaft 2, which rotatable shaft 65 is provided with the blades or fingers 3, which blades or fingers are preferably located as illustrated in Figs. 11 and 14; but it will be understood that the exact location of the blades or fingers 3 is immaterial, inasmuch 70 as the object and purpose hereinafter described can be carried out without reference to the exact location of said blades or fingers.

The rear end or portion of the handpiece proper is provided with the screw-threaded 75 portion 4, which screw-threaded portion is entered into the screw-threaded recess 5, thereby connecting the clutch-cylinder 6 to the handpiece 1. Within the cylinder 6 is located the sliding clutch 7, said clutch being 80 so formed that it will move back and forth freely, as hereinafter described.

The sliding clutch 7 is provided with the slot or kerf 8, which slot or kerf is for the purpose of receiving the fins or fingers 9, 85 which fins or fingers are securely connected to the shaft 10, said shaft 10 being connected to an ordinary flexible rotatable shaft and power transmitted to the shaft 10 by means of the ordinary flexible shaft driven by an ordinary dental engine or from any other source of power.

For the purpose of holding the shaft 10 in proper position the screw-threaded disk 11 is provided, which screw-threaded disk is connected to the cylinder 6, as illustrated in Figs. 1 and 2.

For the purpose of connecting the sleeve or casing surrounding the flexible shaft the screw-threaded disk 12 is provided. The 100

flexible shaft and its sleeve are not illustrated, inasmuch as their construction is common and forms no particular part of the present invention.

5 For the purpose of providing a means for allowing the sliding clutch 7 to be moved back and forth, as hereinafter described, within the cylinder 6 the slot or kerf 8 is formed of such a depth that the fins 9 will at no time be disconnected from said slot or kerf.

The sliding clutch 7 is provided with the annular groove 13, which annular groove is for the purpose of receiving the pin or point 14, 15 located upon the bottom or under side of the sliding plate 15, said pin being formed of such a length that it can be passed through the elongated slot 16 and entered in the annular groove 13.

20 For the purpose of holding the sliding plate 15 in proper position said plate is provided with the open recesses or slots 17, which open slots are so arranged that they will receive the lugs 18, which lugs are located upon the cylinder 6, substantially as illustrated in Fig. 10, and for the purpose of preventing any rocking movement of the sliding plate 15 the cylinder 6 is provided with the flat surface or portion 19.

30 For the purpose of providing a means for operating the sliding plate, which in turn imparts a reciprocating movement to the sliding clutch 7, the forward-extending bar or rod 20 is provided, which rod is pivotally connected 35 to the sliding plate 15, as illustrated in the drawings, and is preferably roughened upon its upper forward portion for the purpose of preventing the thumb or finger of the operator from slipping.

40 It will be understood that the bar or rod 20 should be formed light and may be bent from a single piece of wire and the rear ends of the wire turned so as to be received in the apertures 21, formed in the edges of the sliding plate 17.

In use when it is desired to impart rotary motion to the tool placed in the handpiece the bar or rod 20 is moved forward, carrying with it the sliding plate 15, which in turn 50 moves the sliding clutch forward and brings the fingers 22 into engagement with the fins or fingers 3, located and connected to the shaft 2. When it is desired to stop rotary motion of the tool, the bar or rod 20 is moved 55 backward, thereby disengaging the fingers 22 from the fins 3 and allowing the clutch 7 to rotate independent of the shaft 2, together with the different parts connected thereto.

For the purpose of protecting and covering 60 the sliding plate 15 the cap 23 is provided, which cap is located upon the lugs 18 and

connected by means of suitable screws, such as 24.

For the purpose of holding the rod or bar 20 in proper relation with reference to the 65 hand-tool 1 the edges of the sliding plate upon its forward end are provided with the grooves 25, and when brought into the position illustrated in the full lines, Figs. 1 and 2, said adjacent portions will be automatically seated in the grooves.

Within the disks 12 is located the block 26, which block is securely attached to the shaft 10 in any convenient and well-known manner.

Having fully described my invention, what 75 I claim as new, and desire to secure by Letters Patent, is—

1. In a stop attachment for dental hand-pieces, the combination of a handpiece provided with a rotatable shaft, having connected thereto fins, a cylinder connected to the handpiece and having located therein a sliding clutch said sliding clutch provided with the annular groove and the slot 8, the sliding plate provided with recesses, lugs located 85 upon the cylinder and in the grooves of the sliding plate, and a shaft provided with fingers located in the slot of the sliding clutch, substantially as and for the purpose set forth.

2. The combination of a handpiece, a cylinder connected thereto, a sliding clutch located in the cylinder and a sliding plate connected to the cylinder, means for sliding the clutch with the plate, a bar pivotally connected to the sliding plate and provided with 95 a roughened upper surface, and grooves located upon the edges of the sliding plate to receive the members of the rod or bar, and means for connecting the sliding clutch with the tool-shaft, substantially as and for the 100 purpose specified.

3. The combination of a handpiece, a cylinder connected thereto, said cylinder provided with a flat or plain surface formed upon a portion of its periphery, lugs located upon 105 the flat or plain surface, a sliding plate provided with open slots and the lugs located in the open slots, a pin or point connected to the sliding plate and adapted for engagement with an annular groove formed upon the periphery of the sliding clutch and the sliding clutch located intermediate the power-shaft and the tool-shaft, substantially as and for the purpose specified.

In testimony that I claim the above I have 110 hereunto subscribed my name in the presence of two witnesses.

HUGH BURT MITCHELL.
